[57] CLAIM

The ornamental design for a handbag light, substantially as shown and described.

DESCRIPTION

FIG. 1 is a front elevational view of a handbag light, showing my new design.

FIG. 2 is a rear elevational view of my handbag light.

FIG. 3 is a right side elevational view of my handbag light.

FIG. 4 is a left side elevational view of my handbag light.

FIG. 5 is a top view of my handbag light.

FIG. 6 is a bottom view of my handbag light.

The light is intended for use in the lining of a handbag.
